Patented May 9, 1961

190,280

BASE UNIT FOR A STORE SERVICE TRUCK

Ralph G. Hummer, Oklahoma City, Okla., assignor to
Sylvan N. Goldman, Oklahoma City, Okla.

Filed May 13, 1960, Ser. No. 60,572

Term of patent 14 years

(Cl. D14—3)

Fig. 1 is a perspective view of a base unit for a store service truck showing my new design;

Fig. 2 is a side elevation thereof;

Fig. 3 is a top plan view; and

Fig. 4 is an end elevation.

I claim:

The ornamental design for a base unit for a store service truck, as shown.
